UNITED STATES PATENT OFFICE.

JOHN H. IRWIN, OF MORTON, PENNSYLVANIA.

CARBON CONTACT FOR TELEPHONES.

346
X 3063

SPECIFICATION forming part of Letters Patent No. 238,784, dated March 15, 1881.

Application filed January 29, 1881. (No model.)

To all whom it may concern:

Be it known that I, JOHN H. IRWIN, of Morton, Delaware county, Pennsylvania, have invented a new and useful Improvement in Carbon Contacts and Buttons for Telephone or Microphone Transmitters, of which the following is a specification.

My invention relates to a method of treating the carbon buttons or contacts of a battery-transmitter with a view to eliminating, so far as may be, the crackling or sputtering noises that accompany the transmission of articulate sounds and interfere with the distinctness of the received articulations, and that are in all cases a source of annoyance. These foreign and disturbing sounds have been attributed to many causes, such as disturbance in the electrical conditions of the atmosphere, earth-currents, &c. My observations and experiments have led me to believe that they are in large measure due, where battery or contact transmitters are used, to the electrical decomposition of aqueous vapor or moisture, which, by reason of the structural nature of the carbon, is present in its pores or interstices, to a greater or less degree dependent upon the hygrometric condition of the surrounding atmosphere, and that the disturbing cause is, in fact, the sudden liberation of constituent gases by electrolysis.

In order to remove this source of annoyance and confusion in the reception of the transmitted sounds, I have conceived the idea of moistening or saturating the carbon with a liquid or material not readily decomposable by the action of the electric current, but which will exclude aqueous vapor or moisture from the body or pores of the carbon without interfering with its proper action as a tension-changer. To accomplish this object I moisten or saturate the carbon with a non-conducting liquid or substance, such as petroleum or mineral hydrocarbon, animal or vegetable oils or fats, or paraffine.

Various methods may be adopted for applying the non-conducting substance. Where such substance is a liquid it is simply necessary to heat the carbon to a sufficient degree to expel any aqueous moisture, and then ap-

ply the liquid by pouring it over the carbon, or by dipping the carbon into it.

I have obtained excellent results by the application of ordinary petroleum. It is, of course, desirable in all cases that the non-conducting substance should be as free as possible from acids, or any material that would be readily decomposable, or would attack the metallic contact-points ordinarily used in conjunction with carbon buttons. A carbon button treated in this way may be used in any form of battery-transmitter, and is applicable not only to those forms in which metallic electrodes are used in contact with the carbon, but also to those in which both contacts are of carbon. When such non-conducting liquid is of a fatty or oily nature, as is ordinarily the case, it acts to prevent the secretion or absorption of moisture by its repellent action, as well as by filling the pores or interstices of the button.

This method of treating carbon buttons may obviously be applied to other resistance-contacts, which, by reason of their structural nature, may absorb or hold aqueous vapors or moisture; and I contemplate, therefore, applying the same treatment to resistance-pieces formed of finely-divided metals or conductors compacted into shape in any suitable manner, as well as to any other contact piece or resistance whose structure is in any degree porous.

As an additional result flowing from the use of a carbon contact treated in the manner above described, I have found that the point of the metallic electrode is less liable to become oxidized, and that the instrument is more constant in its action and less liable to get out of adjustment.

I do not wish to be understood as limiting myself to the particular non-conducting liquids or substances above mentioned, as it is within the scope of my invention to use any substances not readily decomposed by the electric current that can, by filling the pores or interstices of the conducting-button, exclude aqueous vapor or moisture without at the same time interfering with the action of the button or electrode as a resistance-contact.

What I claim as my invention is—
1. A telephone or microphone resistance-

contact treated or saturated with a non-conducting substance or liquid.

2. A carbon button or contact resistance moistened or treated with a non-conducting substance or liquid, substantially as described.

3. A carbon resistance-piece moistened or treated with a hydrocarbon liquid or substance.

4. A carbon resistance-piece moistened or saturated with petroleum, substantially as and to for the purpose described.

J. H. IRWIN.
